UNITED STATES PATENT OFFICE.

WILLIAM C. TEMPLE, OF MUNSON, FLORIDA.

REINFORCED-CONCRETE RAILROAD TIE.

Application filed November 1, 1922. Serial No. 598,353.

To all whom it may concern:

Be it known that I, WILLIAM C. TEMPLE, a citizen of the United States, residing at Munson, in the county of Santa Rosa and State of Florida, have invented certain new and useful Improvements in a Reenforced-Concrete Railroad Tie; and I do hereby declare the following to be a full, clear, and exact description of the invention, such as will enable others skilled in the art to which it appertains to make and use the same.

The invention has relation to cross ties for railways and relates more particularly to ties which are practically indestructible and constructed of concrete or other suitable plastic material, the principal object being to strengthen and reenforce ties of this nature.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the application,

Figures 1 and 2 are opposite views, respectively, of a reenforced concrete railroad tie embodying the invention, the rails being in section.

Figure 3 is a top plan view of the metal reinforcement, the dotted lines indicating the outline of the tie and the bolts for securing the rails being in section,

Figure 4 is a vertical section on the line 4-4 of Figure 3, looking in the direction of the arrows, and

Figure 5 is a transverse section on the line 5-5 of Figure 4, looking to the right as designated by the arrows.

Corresponding and like parts are referred to in the following description and designated in the several views of the drawings by like reference characters.

The numeral 1 designates the body of the tie which may consist of concrete or other plastic material, the same being molded and strengthened by an embedded reinforcement.

The metal reinforcement comprises longi-

tudinal plates 2, end tie plates 3, intermediate tie rods 4 and anchoring cross rods 5 which are set staggering and supported in the plates 2 with opposite ends projecting. Some of said cross rods 5 have their projecting ends threaded and receive nuts 6 which constitute abutments to positively engage the concrete or other material from which the tie is formed. The tie plates 3 and tie rods 4 are formed with reduced portions which extend through openings in the longitudinal plates 2 and have their projecting ends upset or riveted, whereby to retain the parts when assembled. Vertically disposed tubes 7 are embedded in the tie when the same is molded and provide passages for bolts 8, whereby the rails 9 are secured to the tie through the instrumentality of clips 10 which engage the threaded ends of the bolts. Rail braces 11 are also secured to the tie by bolts 8 and these braces 11 engage a side of the rail beneath the head thereof.

It will be understood from the foregoing that the tie is strengthened and reenforced and will not come apart, even though it should crack from any cause. The nuts 6 and the heads of the bolts are disposed outwardly from the plates 2 and being embedded in the material of the tie, prevent side portions of the latter scaling and breaking away.

What is claimed is:

A tie having a concrete body, a frame embedded therein, having longitudinal plates, cross rods spanning and extending through and beyond the outer sides of the plates, cross rods having shoulders engaged by the inner sides of the plates, nuts threaded on said cross rods beyond the outer sides of the plates and terminating relatively close to the sides of the body and being completely embedded in the body, and positioning tubes for rail securing bolts disposed through the body at a right angle to said cross rods, and one of said tubes passing between and directly engaging certain of said cross rods.

In testimony whereof I affix my signature in presence of two witnesses.

WILLIAM C. TEMPLE.

Witnesses:

E. E. STEWART,

T. W. JONES.
